CLAIM

I claim the ornamental design for a single compartment hinged container, as shown and described.

DESCRIPTION

FIG. 1 is a perspective view of a single compartment hinged container showing my new design, with the container partially open;

FIG. 2 is a perspective view thereof, with the container closed;

FIG. 3 is a top plan view thereof, with the container fully open;

FIG. 4 is a bottom plan view thereof, with the container fully open; and,

FIG. 5 is a side plan view thereof, with the container fully open.
